UNITED STATES PATENT OFFICE.

ELBRIDGE WHEELER, OF BOSTON, MASS., ASSIGNOR TO HIMSELF, WARE B. GAY, AND GEORGE W. GOGIN, TRUSTEES, ALL OF SAME PLACE.

MOLD.

SPECIFICATION forming part of Letters Patent No. 361,798, dated April 26, 1887.

Application filed May 6, 1886. Serial No. 201,322. (No model.)

To all whom it may concern:

Be it known that I, ELBRIDGE WHEELER, of Boston, county of Suffolk, and State of Massachusetts, have invented an Improvement in 5 Molds, of which the following description, in connection with the accompanying drawings, is a specification, like letters on the drawings representing like parts.

My invention has for its object to provide 10 molds with means, as will be described, whereby parallel ingots may be cast of uniform area in cross-section from top to bottom, my invention also having for its object to prolong the life of the mold in which said parallel ingots 15 are cast.

Molds such as ordinarily found in steel 20 plants, and usually composed of cast-iron, have been made tapering, in order to facilitate the withdrawal of the mold from the ingot cast 25 within it.

In casting the steel or other metal in the kind of molds referred to it frequently happens that the cast metal sticks to the walls of the mold into which it has been cast. In such 25 instances it is necessary to pound or otherwise subject the mold to strain, in order to disassociate the metal and the mold.

The primary object of this invention is to 30 prolong the life of the mold by preventing the metal from sticking to the walls of the mold, thereby obviating pounding and straining the said mold.

I accomplish my object by means of four independent rectangular plates set within the 35 flask or mold, the plates forming when in position the inner walls of the mold.

Figure 1 represents in sectional elevation one form of mold provided with plates by which to practice my invention; Fig. 2, a top 40 view of Fig. 1; Fig. 3, a top or end view of a modified form of mold by which to produce a parallel ingot; Fig. 4, a sectional view of Fig. 3 on line $x-x$; Fig. 5, an isometric view of a parallel ingot which may be produced in the 45 mold, Figs. 1 and 3; Fig. 6, a detail to be referred to; and Fig. 7, a similar view to Fig. 3, with the sand removed, showing the upper band encircling and holding together the walls of the mold.

50 Figs. 1 and 2 show one form of my improved

mold, the same being composed of four independent rectangular metal plates, b , inclosed by a flask, (represented as of two parts, a a' ,) preferably of cast-iron, the parts of the flask being shown as tapering, to permit the section 55 a' to be readily withdrawn from between the plates and the section a . The plates b at their junction with each other (see Fig. 2) are recessed to receive sand, soapstone, or other suitable material to prevent the passage of 60 molten metal between them.

In Figs. 3 and 4, showing a modification of my invention, the metal plates b , having bent lugs d^4 at their outer sides, are set within the flask a . (Shown as a parallel-sided box.) The 65 lugs d^4 of the plates support metal bands d^5 , (see Figs. 4 and 6,) and wedges e are employed between the bands and plates to force closely together the joints between the plates b . These plates are surrounded by sand, soapstone, or 70 other equivalent material, d' , to prevent the cast metal running through the joints of the said plates. The band d^5 is sufficiently large to permit the plates b to fall away from one another when the mold is not in use, the said plates 75 being brought into close contact, as shown in Fig. 3, by wedges e , inserted between the band d^5 and the plate b , when it is desired to use the mold.

With the mold shown in Fig. 3 the metal 80 cast into the said mold is allowed to set, and after said metal has set the flask or mold a will be withdrawn, permitting the sand to fall away from the plates b , and the wedges e are then withdrawn, thereby allowing the said plates 85 to be easily removed from the ingot.

With the mold shown in Figs. 1 and 2 the section a' is fitted into the section a , which latter rests upon any suitable or ordinary base or support, and the plates b are then arranged 90 inside the section a' , to form the inner walls of the mold. After the plates b have been placed in position within the section a' , the recesses in the corners of the said plates are filled in with sand, as shown in Fig. 2. The metal is 95 then cast into the mold, and after it has set and the ingot has become sufficiently hard the section a' is withdrawn from between the section a and the plates b by means of hooks engaging loops d^0 , or in other suitable manner.

I do not herein broadly claim a mold made of removable sections united by a tongue-and-groove joint, such a mold being shown in English Patent No. 2,043 of 1868.

5 I claim—

1. The inner mold consisting of the four independent rectangular plates *b*, the ends of each of two plates abutting against the faces of each of the other two plates, and not otherwise united or connected, combined with the outer-mold and the packing or filling between the two molds, substantially as described.
- o

2. A mold for casting, comprising the rectangular independent plates *b*, provided with hooks, a surrounding band arranged in said hooks and wedged to hold it there, and an external flask, substantially as described.

In testimony whereof I have signed my name to this specification in the presence of two subscribing witnesses.

ELBRIDGE WHEELER.
